UNITED STATES PATENT OFFICE.

CHARLES LANE, OF JEFFERSON, WISCONSIN.

DISAPPEARING HEADREST.

Application filed November 22, 1926. Serial No. 150,019.

My invention relates to disappearing head rests or chairs, more particularly barbers' and dentists' chairs. Chairs of this character are often provided with adjustable head rests which move down behind the back of the chair, or rest on top of the chair back when in their lowermost position. But with such arrangements, the head rests are always more or less in the way, and occasion a considerable degree of inconvenience.

My object is to provide a barber's chair with a pocket in the back thereof, with an adjustable head rest mounted therein, and adapted to move up out of the pocket into adjusted positions when in use, and to move down into the pocket entirely out of view and out of the way when not in use.

Another object is to provide a device of this character which, when moved upwardly out of the pocket into operative position, will automatically assume the proper inclined position to most comfortably receive the head of the occupant of the chair.

A still further object is to provide a head rest of the character described having means for carrying and properly housing a roll of paper for use on the pad of the head rest.

Still another object is to provide the head rest with a pivoted cutter for the paper, so arranged that when the cutter is swung forward on its pivot, it presents a sharp cutting edge upon which a portion of the paper may be easily severed from the roll, but when returned to its normal position will be out of the way with its edge not exposed.

The invention consists in certain novel features of construction and arrangement of parts, as will be hereinafter described and claimed, reference being had to the accompanying drawings, in which:—

Fig. 1 is a side elevation of a chair provided with my improvement. Fig. 2 is a sectional view on an enlarged scale of the upper portion or head rest proper of my device, with the pad removed from the face thereof. Fig. 3 is a side elevation on a different scale, of my improved head rest and the container therefor, the latter being shown in section. Fig. 4 is a front view of the container with an opening broken away to disclose the slide arrangement which carries the adjusting bar of the head rest. Fig. 5 is a front view of the head rest when in its folded condition when in the container, but with the pad and transverse springs supporting the same, removed to

disclose the other parts; and, Fig. 6 is a rear view of the upper part of the container, showing the notch therein for the reception of the lifting knob of the device.

Referring further to the drawings, the numeral 1 indicates the head rest proper, which carries on its front face a pad 2, supported on the springs 3 which extend transversely across the face of the head rest. The head rest is supported on the upper end of a vertically adjustable bar 4 which is provided throughout its length with ratchet notches 5, and terminates at its upper end in a right-angled section 6 having at its inner end a pivotal connection 7 upon which the head rest has a limited rocking movement, as will now be explained. The rear wall of the head rest is provided with an opening 8 therein for the reception of the upper end of the section 6 of the bar 4. At the opposing sides of this opening are the ears 9 provided with suitable bores for the ends of the pivot 7.

At the upper side of this opening 8 is a downward and inward extension 10, the under face 10^a of which serves as an abutment to limit the rocking movement of the head rest on the right-angled section 6 at the upper end of the adjusting bar 4. Rigidly secured to the under side of the ears 9 is a downwardly extending vertical section 11 having on its outer face a recess 12 in which a spring 13 is seated. The adjusting bar 4 is provided on its inner face with a boss 14 around which the outer end of said spring is received. This is a compression spring, and therefore operates to throw the lower end of the head rest away from the adjusting bar to give the head rest, when in operative position, a suitable degree of inclination to said bar, as indicated in Figs. 1 and 3.

The head rest 1 and the supporting bar 4 are so arranged relatively to each other that their rear faces are in alinement with each other when the lower end of the head rest is swung inwardly toward said bar preparatory to being moved down into the container 15. This container is provided on its rear inner wall with guides 16 for the adjusting bar 4. At the upper edge of its rear side it has a notch 17^a adapted to receive the lifting knob 17; and further down it is provided with an opening 18 through which the upper bent end of the pawl 19 is passed to engage the notches 5 of the adjusting bar 4.

At the lower end of the head rest is a roll of paper 20^a carried on a suitable rod 20 pivotally mounted between the sides of the container. At one end of this rod the side 5 of the head rest is slightly cut away as indicated at 21, and this slight recess is overlapped by a flat spring 22 secured to said side at its upper end by a screw or rivet 23, and at its lower free end provided with a bore 24 into which the end of the rod 20 is received. The spring is movable into the recess 21 to permit the end of the rod 20 to enter the bore 24 at the lower end of said 10 spring.

15 Pivottally mounted on the top of the head rest is the paper cutter 25 provided with a beveled cutting edge 26. Normally this cutter is swung backwards as shown in Fig. 2 so that its cutting edge is lying in flat 20 engagement with the top of the head rest, and therefore said edge is not exposed. But when it is desired to use the cutter for severing a piece of paper from the roll 20^a, it is swung forward so that its upper edge 25 overhangs the upper forward edge of the head rest and is fully exposed ready for use, the pivot point of the cutter being slightly nearer to the forward edge of the head rest than to the rear edge. The downwardly extending section 11 of the head rest terminates at its lower side in a foot portion 27 which forms a stop for the head rest when its lower end is moved inwardly toward the 30 adjusting bar 4 to a point where the rear wall of the head rest and said bar are in 35 parallelism with each other, so that the inclined projection 10 limits the rocking movement of the head rest in one direction, and the foot 27 in the other direction.

40 The operation of my device is very simple: The back of the chair with which it is to be used is provided with a suitable pocket or opening for the reception of the container 15, and the head rest proper is mounted in this container on the vertically adjustable 45 bar 4 which has the ratchet notches 5 on its rear side adapted to be engaged by the pawl

19 as the bar is moved upwardly from notch to notch. The hand knob 17 forms a convenient means for elevating the head rest. 50 When the head rest is moved upwardly above the top of the container 15, the spring 13 automatically tilts the lower end of said rest into the position indicated in Fig. 1, ready 55 for use.

When it is desired to apply a new piece of paper to the pad 2 of the head rest, the desired amount of paper is unwound from the roll 20^a; the cutter 25 is swung forward, and the paper is cut or torn off on the 60 beveled edge 26. The cutter is then swung back into its normal position, as indicated in Fig. 2, to bring its cutting edge out of position to be contacted with.

From the foregoing it will be seen that I 65 have provided a device which can be produced at a very moderate cost, and which will be a great convenience to persons using chairs of the character referred to.

Having now described my invention, what 70 I claim as new and desire to protect by Letters Patent is:—

In a device of the character described, the combination with a head rest, of a supporting bar having an angular upper end extending inwardly into the head rest, and pivoted at its inner extremity to the head rest for the same to rock thereupon; an inclined rigid stop carried by the head rest and arranged to come into abutting engagement 75 with the angular upper end of the supporting bar to limit the rocking movement of the head rest thereon in one direction; rigid means also carried by the head rest for contacting with the supporting bar below its 80 angular upper end to limit its movement in the opposite direction; a spring for normally pressing the head rest in one direction; and a container for carrying the supporting bar and for receiving the head rest thereinto 85 and housing the same when not in use.

In testimony whereof I affix my signature.

CHARLES LANE.
